UNITED STATES PATENT OFFICE.

NEAL SMITHBACK AND WILLIAM HENRY MEIER, OF MADISON, WISCONSIN.

GRAIN-DOOR.

1,340,506.

Specification of Letters Patent. Patented May 18, 1920.

Application filed June 26, 1919. Serial No. 306,946.

To all whom it may concern:

Be it known that we, NEAL SMITHBACK and WILLIAM HENRY MEIER, citizens of the United States, and residents of Madison, in 5 the county of Dane and State of Wisconsin, have invented certain new and useful Improvements in Grain-Doors, of which the following is a specification.

Our invention relates in general to grain 10 doors and more particularly to that type of grain door which swings horizontally and which is adapted most especially for use with grain cars, grain storage structures or the like.

15 An important object of our invention is to provide a grain door of this type with an outwardly swinging section and inwardly swinging sections, the inwardly swinging sections being positively prevented from 20 swinging outwardly beyond the closed position of the door.

Another object of our invention is to provide the inwardly swinging sections with 25 means whereby they are swung to and normally held in predetermined position whether this predetermined position be the closed position of the doors when in use or the open position of the doors flush against the wall of the storage structure when not in 30 use.

Another object is to provide means whereby the doors will be automatically set in snug and leak-tight relation in closed position and may partake automatically of all 35 the movements necessary in the different phases of the operation of opening and closing.

Other objects and advantages reside in certain novel features of the construction, 40 combination and arrangement of parts and will become apparent as the description proceeds, reference being had to the accompanying drawings, forming a part of this specification, in which

45 Figure 1 is an outside elevation of the door, a portion of the upper section being broken away,

Fig. 2 is a plan view in section along the line 2—2 of Fig. 1,

50 Fig. 3 is an inside elevation of the door, a portion of the upper section being broken away,

Fig. 4 is an end elevation of the door, the wall of the car or storage structure being 55 shown in section,

Fig. 5 is a top plan view of the upper swinging sections,

Fig. 6 is an inside elevation of the upper swinging sections,

Fig. 7 is an end elevation of the upper 60 swinging sections, the adjacent portion of the car wall being shown in section,

Fig. 8 is a top plan view of the lower sections, the positions taken by the inwardly swinging sections and the outwardly swinging section being shown in dotted lines, 65

Fig. 9 is an inside elevational view of the lower sections, and

Fig. 10 is an end elevational view of the lower sections. 70

Referring to the drawings the numeral 12 indicates a sill mounted on the floor of the car or storage structure, 13 the wall of the car or storage structure and 14 the door opening. It is to be understood that if desired the sill may be omitted as the floor of the car or storage structure may be adapted to serve the purposes of the sill. 75

Vertical pintle rods 15 are seated in the sill 12 and are journaled in collars 16 fixed 80 to the wall 13. The pintle rods and journal collars are positioned a substantial distance from the door opening for a purpose to be hereinafter more fully described.

The swinging sections composing the door 85 include upper inwardly swinging sections 17, 18, 19, and 20, lower inwardly swinging sections 21 and 22 and a lower outwardly swinging section 23. The inwardly swinging sections are hinged to the vertical pintle 90 rod 15 and the outwardly swinging section is hinged to the lower inwardly swinging section 22 in a manner to be hereinafter more fully described. It is to be understood that while only four of the upper inwardly 95 swinging sections are shown in the drawings, any desired number may be employed.

The swinging sections, with the exception of the lower outwardly swinging section 23 and the coöperating structure of the swinging section 22, are identical and comprise hinge end pieces consisting of a hollow body portion 24 having an open end to provide a socket and a closed end 25 integral with the body portion. Apertured ears 26 are 100 formed integral with the closed end and are mounted upon the pintle rod 15. These apertured ears are preferably disposed adjacent the upper and lower ends of the hinge end pieces so as to bear against the collars 110

- 16 when in position. A panel 27 has its inner and outer ends reduced and its inner end is accommodated or housed in the socket of the hinge end piece.
- 5 Located in the inner end of the socket and secured to the wall 25 is a spring 28. This spring 28 is preferably secured to the wall by means of a rivet, bolt or like fastening means, and is so arranged that its end bears 10 against the inner end of the panel and tends to normally space the same from the inner end of the socket and to resiliently oppose movement of the panel beyond a certain point toward the inner wall of the socket.
- 15 A meeting end piece 29 consists of a hollow body portion having an opened end to provide a socket and a closed outer end and is disposed on the outer end of the panel, the reduced portion of the panel being accommodated or housed in the socket of the 20 meeting end piece. The outer closed end of the meeting end piece presents a substantial face which abuts against a similar face presented by the adjacent meeting end piece when a pair of the swinging sections are in closed position. Each pair of swinging sections have the meeting faces of the 25 end pieces 29 provided with a tongue 30 and groove 31 which interfit in the closed position of the swinging sections.
- 30 A coil spring 32 is mounted on the pintle rod between the apertured ears of each of the upper sections and has one end abutting one of said ears and the other end abutting 35 against a shoulder or the like provided on the collar 16. This spring is normally so arranged as to tend to swing the upper sections to closed position and to resiliently hold them in this position. It is to be noted, 40 however, that this spring may be reversed so that its tendency will be to swing the sections around to position flush against the car wall in the event it is desirable to have the door opening unobstructed and the 45 swinging sections entirely out of the way.
- The lower swinging sections 21 and 22 are mounted on the pintle rod in the same manner as the upper inwardly swinging sections and all of these sections have a substantial 50 portion of their length bearing against the car wall and this feature of arrangement absolutely precludes any possibility of the inwardly swinging sections moving outwardly beyond their closed position. The inwardly 55 swinging section 22 is approximately half the length of the other sections and has its outer end constructed so that the outwardly swinging section 23 may be hinged thereto as shown in the drawing. The outwardly 60 swinging section 23 and the lower inwardly swinging section 21 have meeting end pieces constructed and arranged identical with the meeting end pieces of the upper inwardly swinging sections.
- 65 The lower outwardly swinging section

and the lower inwardly swinging section are provided with means for locking them together in closed position and the lower outwardly swinging section and the lower inwardly swinging section are provided with 70 identical means for locking them individually to the car or structure floor in closed position. This last-mentioned locking means comprises a bolt 33 mounted on the outside of the sections and adapted to be seated in a keeper in the car floor. This bolt may be spring retracted and is provided with means for retaining it in locked position such as a detent 34. The means for locking the sections together comprises a 75 locking bar 35 pivoted to the inwardly swinging section and adapted to be seated in locked position in a keeper 36 secured to the outwardly swinging section as shown in Fig. 1. The adjacent horizontal faces 80 of all of the sections are beveled as shown in the drawing so that they overlap in closed position and provide a snug and leak-tight joint.

In practice when the car or storage structure is loaded with grain the parts are in the position shown in Fig. 1, the weight of the grain aiding in maintaining the inwardly swinging sections in closed position and the outward swinging section being 90 locked in closed position by the locking means described. When it is desired to unload the grain the detent is operated to release the locking bolt and the locking bar is removed from the keeper to allow the section 23 to swing outwardly as shown in Fig. 8. In the event it is not desirable to use the doors or to house them in open position by reversing the spring as previously described the pintle rods may be removed and the sections taken down.

We claim:

1. A grain door consisting of horizontally swinging sections including hinge end pieces each provided with a socket, panels 110 each having their inner end accommodated in said socket, meeting end pieces each having a socket accommodating the outer ends of said panels, said meeting end pieces having meeting faces of substantial extent, one of said faces being provided with a groove and the other of said faces being provided with a tongue adapted to fit in said groove and spring means secured to the inner wall of the socket in said hinge end piece and bearing against the adjacent end of said panel whereby the meeting faces of the meeting end pieces are forced squarely and snugly against each other in closed position.
2. A grain door consisting of horizontally 125 swinging sections including hinge end pieces each provided with a socket, panels each having their inner end accommodated in said socket, meeting end pieces each having a socket accommodating the outer ends of said 130

- panels, said meeting end pieces having meeting faces of substantial extent and spring means secured to the inner wall of the socket in said hinge end piece and bearing against 5 the adjacent end of said panel whereby the meeting faces of the meeting end pieces are forced squarely and snugly against each other in closed position.
3. A grain door consisting of pintle rods, 10 horizontally swinging sections including hinge end pieces each provided with a socket, panels each having their inner end accommodated in said socket, meeting end pieces each having a socket accommodating 15 the outer ends of said panels, said meeting end pieces having meeting faces of substantial extent, and spring means secured to the inner wall of the socket in said hinge end piece and bearing against the adjacent end 20 of said panel, whereby the meeting faces of the meeting end pieces are forced squarely and snugly against each other in closed position and means for swinging the sections to closed position.
- 25 4. A grain door consisting of pintle rods, horizontally swinging sections including hinge end pieces each provided with a socket, panels each having their inner end accommodated in said socket, meeting end 30 pieces each having a socket accommodating the outer ends of said panels, said meeting end pieces having meeting faces of substantial extent, and spring means secured to the inner wall of the socket in said hinge end 35 piece and bearing against the adjacent end of said panel, whereby the meeting faces of the meeting end pieces are forced squarely and snugly against each other in closed position.
- 40 5. A grain car door comprising a vertical pintle rod, journals for said pintle rod each provided with a shoulder, a swinging section including a panel, and a hinge end piece, said hinge end piece having apertured ears 45 integral therewith and pivoted on said vertical pintle rod, and a coil spring mounted on said pintle rod and having one end engaged with one of said ears and the other end of said spring engaged with the shoul- 50 der of said journal.
- 55 6. A grain door comprising upper inwardly swinging sections, spring means adapted to maintain said upper inwardly swinging sections in closed position, a lower outwardly swinging section and locking means adapted to maintain said outwardly swinging section in closed position.
7. A grain door comprising upper inwardly swinging sections, spring means
- adapted to maintain said upper inwardly swinging sections in closed position and a lower outwardly swinging section.
8. A grain door comprising swinging sections, each section of which includes a panel, a hinge end piece provided with a socket to receive one end of said panel and spring means interposed between the inner wall of said socket and adjacent end wall of said panel.
9. A grain door comprising horizontally 70 swinging sections, a panel in each of said sections, meeting end pieces each provided with a socket to accommodate the outer end of each of said panels, hinge end pieces each provided with a socket to accommodate the 75 inner end of each of said panels, and spring means mounted in the inner end of each of the sockets of said hinge end pieces to normally urge said panels outwardly therefrom.
- 80 10. A grain door comprising a swinging section consisting of a panel, including a hinge end piece at the inner end of said panel, and means urging said panel away from said hinge end piece.
- 85 11. A grain door for grain cars, storage structures or the like comprising the combination with the wall of the structure provided with a door opening therein, of pintle rods, journals for said pintle rods spaced a 90 substantial distance from said door opening and horizontally swinging sections hinged on said pintle rods whereby a substantial portion of each horizontal swinging section abuts against the wall of said structure in closed position to limit the outward movement of said sections.
- 95 12. A grain door consisting of swinging sections including hinged end pieces, meeting end pieces having meeting faces, panels 100 carried by said end pieces, and means carried by one of said end pieces and engageable with said panels to force the meeting faces of said meeting end pieces squarely and snugly against each other in closed position.
- 105 13. A grain door consisting of swinging sections including hinged end pieces provided with sockets, meeting end pieces provided with sockets and having meeting faces, panels mounted in the sockets of said 110 end pieces and spring means carried by one of the said pieces and engageable with said panels to force the meeting faces of said meeting end pieces squarely and snugly against each other in closed position.

NEAL SMITHBACK.
WILLIAM HENRY MEIER.
